United States Patent Office

Des. 222,417
Patented Oct. 19, 1971

222,417

TEXTILE FABRIC

John W. Rock, Wyckoff, N.J., assignor to Cannon
Mills Company, Kannapolis, N.C.

Filed Aug. 7, 1970, Ser. No. 24,373

Term of patent 14 years

Int. Cl. D5—05

U.S. Cl. D92—1

The figure is a top plan view of a textile fabric showing my new design with the area enclosed within the dotted lines thereof corresponding to one repeat of the design.

I claim:

The ornamental design for a textile fabric, substantially as shown and described.
